TEMPERATURE-INDEPENDENT OSCILLATORY CIRCUITS

Herbert Muth and Wilhelm Runge, Berlin, Germany, assignors to Telefunken Gesellschaft für Drahtlose Telegraphie m. b. H., Berlin, Germany, a corporation of Germany

Application April 19, 1934, Serial No. 721,371
In Germany April 19, 1933

1 Claim. (CL 250—40)

The present invention relates to means and apparatus for rendering tuned circuits and like parts of radio transmitting and receiving apparatus and wave meters independent of temperature changes.

High frequency oscillatory circuits whose natural frequency is rendered independent of temperature changes by suitable means are known in the art. However, the use of such devices has heretofore been restricted to transmitters. With the growing use of ultra-short waves, receivers and wave meters must meet particularly high requirements as to selectivity. Hence, in such cases it often becomes necessary to utilize temperature independent circuits.

It is an object of the present invention to devise temperature independent circuits adaptable for use in the devices mentioned above.

In accordance with the invention, reactance elements, for instance, condensers and chokes may be rendered independent of temperature fluctuations as regards the capacity or inductance respectively of the elements, by using as current conducting parts, metal layers upon carriers of ceramic materials possessing an extremely small heat expansion coefficient. As a rule, in such condensers or chokes the ceramic supports for the metal layers are the only parts of the structure formed of material having a small coefficient of expansion. In general, additional members must be provided for the assemblage of the single insulating parts, for the control of variable reactances, and as by-pass means etc.

In accordance with another feature of the invention, such parts are made of metal alloys of a very small heat expansion coefficient, preferably of nickel-steel alloys known by the designation "Invar" or of similar alloys, mainly containing nickel and steel.

Still another feature of the invention relates to a suitable mechanical assemblage of the reactance elements of an oscillatory circuit so that it is independent of temperature changes. It is often necessary, to combine the constituents of the oscillatory circuit, i. e., the chokes and condensers, as closely as possible, in order to use short leads. The invention is based upon the recognized fact that in such a case it is not immaterial in what manner the single reactances of the circuit are arranged with respect to each other. If, for instance, the common mechanical support of two reactance elements has a considerable heat expansion coefficient, it may happen that the distance between the single reactance elements which varies on account of the

expansion of the carrier, due to heat, may change the self inductance or the value of the capacity thereof to such an extent as to cause a notable change in the frequency.

In accordance with the invention, materials having a practically negligible heat expansion coefficient, are used for the mechanical assemblage of single reactance units of oscillatory circuits which are independent in regard to heat. If a member mechanically connecting the two units is also used as an electrical connection, it is suitably formed of a metal alloy possessing a practically negligible heat expansion coefficient. Such alloys are known in the art by various terms such as Invar, Indilatan etc., and contain as an essential if not single constituent a nickel-steel alloy. However, it is also possible to use for mechanically assembling single reactance units, supports of ceramic material likewise of negligibly small heat expansion coefficient. In this case, the electrical connections can be applied to these supports in the form of metallic layers of suitable width, or they may be connected to the support in another manner so that they will not be deformed by the action of heat.

Certain features of the invention are illustrated in the accompanying drawing in which Fig. 1 illustrates the application to a single reactor, as, for instance, a condenser; and Figure 2 illustrates the application of a feature of the invention to a tuned circuit.

In Figure 1 *a* and *b* are supports of ceramic material for the metal layers *c* and *d* respectively. The supports *a* and *b* are of an approximate cup shape. A control axis *e* composed of nickel steel alloy of constant temperature coefficient, for instance Invar, is provided with a screw thread *f*, having a sleeve *g* movably arranged thereon. The sleeve *g* consists of similar material and carries the condenser part *b*. In turning the shaft *e* thereby axially displacing the two cylinders with respect to each other, the capacity can be changed in a manner known per se. In forming the parts *e* and *g* of a suitable nickel-steel alloy, a feature not required as such with regard to electrical considerations (these parts could also be formed of insulating material if they were not intended to serve at the same time for current conduction) a construction is obtained which is substantially independent of temperature changes.

In Fig. 2, *h* is a condenser comprising two supporting members *a* and *b* of ceramic material provided with metal layers *c* and *d* respectively.

A coil *i* has its current conducting winding likewise applied as a layer to a ceramic body *j*.

In Fig. 2 the two oscillatory circuit elements *h* and *i* are connected together by means of the members *l*, *k* which are made of a metal having a negligibly small heat expansion coefficient, as, for instance, the metal alloy known as Invar. In this case, one end of the member *l* is connected to the metallic layer of the condenser *h* at the point *6* while the other end is connected to the top of the coil *i* at the point *7*. The member *k* is arranged so that one end thereof is connected to the metallic layer *c* at the point *8* while the other end is connected to the lower end of the coil *i* as at *9*. In the case of Fig. 2 it will be seen that the members *l*, *k* not only support the condenser and coil but also act as the conductors to form the oscillatory circuit.

What I claim is:

20 In an oscillatory circuit, an inductance coil and a condenser, a plurality of supports said supports being formed of a ceramic material hav-

ing a very small heat expansion coefficient, said coil comprising a region of conducting material spirally formed on one of said ceramic supports, said other support comprising a plurality of sections, one of the sections having a layer of conductive material placed thereon so as to form one electrode of the condenser while another section is provided with a layer of conducting material to form another electrode of the condenser, means comprising a member of metal alloy having a very small heat expansion coefficient for connecting one of the electrodes of the condenser to one end of said coil, means comprising a substantially similar member for connecting the other electrode of the condenser to the other end of the coil, said last two named members being physically connected to said supports for maintaining the supports in proper space relationship with respect to each other.
